(57) **CLAIM**

The ornamental design for a stud with grooves for a fashion article, as shown and described.

DESCRIPTION

FIG. 1 is a top perspective view of a stud showing our new design;

FIG. 2 is a top plan view thereof;

FIG. 3 is a elevational view thereof;

FIG. 4 is a bottom plan view thereof; and,

FIG. 5 is a vertical cross-sectional view of the stud.

The broken lines shown are for illustrative purposes only and form no part of the claimed design.
